UNITED STATES PATENT OFFICE.

JULIUS HEILBRON, OF ST. PAUL, MINNESOTA.

VAPOR-BURNING LAMP.

No. 802,355.

Specification of Letters Patent.

Patented Oct. 17, 1905.

Application filed January 5, 1903. Serial No. 137,814.

To all whom it may concern:

Be it known that I, JULIUS HEILBRON, a citizen of the United States, residing at St. Paul, in the county of Ramsey and State of Minnesota, have invented certain new and useful Improvements in Vapor-Burning Lamps, of which the following is a specification.

My invention relates to improvements in vapor-burning lamps, being designed particularly for vaporizing and burning kerosene; and it consists in the features of construction and combination hereinafter particularly described and claimed.

In the accompanying drawings, forming part of this specification, Figure 1 is a front elevation of my improved lamp. Fig. 2 is a side elevation partly broken away. Fig. 3 is an enlarged section on line *xx* of Fig. 1. Fig. 4 is a section on line *yy* of Fig. 2. Fig. 5 is a view looking down upon the burner with the mantles removed, and Fig. 6 is a section on line *vv* of Fig. 5.

In the drawings, A represents the burner-base, provided with a pair of burners 2. Extending through the base A, intermediate of the burners, is a vertical vaporizing-tube 3. The lower end of the tube 3 is connected by a joint 4 with a tube 5, leading to a source of supply. The flow of oil through the joint 4 is regulated through the medium of the valve-stem 6. Depending from the lower end of the vaporizing-tube 3 is a standard 7, which supports the globe (not shown) in any desired manner. The upper end of the vaporizing-tube 35 opens into the outlet end of the auxiliary tube 8, the upper end of the vaporizing-tube being preferably filled with suitable porous material 9. Arranged in the vertical portion of the auxiliary tube 8 is a rod 10, 40 said rod extending through the bushing 11, which closes the lower end of the auxiliary tube and being provided on its outer end with an actuating finger-piece 12. As shown in Fig. 4, the rod 10 is provided with a pin 13, 45 projecting into a curved groove 14 in the bushing 11, by means of which the turning movement of the rod 10 is limited. Carried by the upper end of the rod 10 is a flexible needle 15, the free end of which projects 50 through the jet-opening 16 in the block 17 in the end of the tube 8. In order to guide the flexible needle centrally through the upper curved end of the tube 8, I provide a curved tube 18, provided at its lower end 55 with a cap 19, which fits over the top of the rod 10 and closes the tube 8, as shown in Fig.

3. The upper end of the guide-tube 18 extends into the block 17. A chamber is thus formed within the tube 8 intermediate of the cap 19 and the end of said tube. 60

20 represents a commingling-tube, the upper open end of which is immediately in front of the jet-opening 16 and the lower end of which is connected with the burner-base and communicates with the burners 65 through the conduit 21.

The lamp is adapted to be supported by a suitable hanger 22, connected with the top of the commingling-tube. Arranged upon each burner is a suitable incandescent mantle 23, 70 supported by a rod 24, secured in a collar 25 by means of a screw 26. The collar 25 is held in adjusted position upon the hanger by means of a suitable screw 27. Carried by the burner-base, intermediate of the burners, is a 75 suitable kindling-pan 28.

In use the oil is fed under pressure through the tube 5, the flow to the vaporizing-tube being regulated by means of the valve-stem 6. When it is desired to use the lamp, sufficient alcohol or oil to start the vaporization of the oil in the vaporizing-tube is placed in the starting-pan 28 and ignited. The vapor generated in the vaporizing-tube passes through the jet-opening 16, the flow of the 85 vapor therethrough being regulated by the needle 15. From the jet-opening the vapor is discharged into the free end of the commingling-tube, drawing in with it air, the commingled air and vapor passing through 90 the commingling-tube 20 to the burners and into the mantles, where it is ignited. The burners now being started, the heat therefrom will continue the vaporizing of the oil in the vaporizing-tube until the supply of oil is shut 95 off. As the vapor passes from the vaporizing-tube it will fill the upper end of the auxiliary tube 8, and the vapor thus stored in the auxiliary tube will assist in causing a steady flow of vapor through the jet-opening. It will be 100 noted also that by having the controlling-needle arranged in an auxiliary tube the interior of the vaporizing-tube is unobstructed and more thorough vaporizing of the oil is secured. 105

Having now described my invention, what I claim as new, and desire to secure by Letters Patent, is—

1. In a vapor-lamp of the class described, the combination with a burner and a commingling-tube communicating with and leading upwardly therefrom, of a vaporizing-tube 110

extending upwardly alongside said burner and connected with a source of fuel-supply, a curved auxiliary tube connected with the upper end of said vaporizing-tube and discharging into the free end of the commingling-tube, and a flexible needle-valve arranged in said auxiliary tube for opening and closing the vapor-escape orifice in the end of said tube.

5 2. In a vapor-lamp of the class described, the combination, with a burner and a commingling-tube communicating therewith and leading upwardly therefrom, of an upwardly-extending straight vaporizing-tube supported alongside said burner, an auxiliary tube carried by the free end of said vaporizing-tube, a flexible needle-valve arranged in said auxiliary tube, and an inclosing guide for said needle-valve.

10 3. In a vapor-lamp of the class described, the combination with a burner, and a commingling-chamber communicating therewith and leading upwardly therefrom, of an upwardly-extending straight vaporizing-tube supported alongside said burner, an auxiliary tube carried by the upper end of said vaporizing-tube, the upper end of said auxiliary tube being curved and discharging into the free end of the commingling-tube, a flexible needle-valve arranged in said auxiliary tube 15 for opening and closing the vapor-escape orifice in the end thereof, and a removable guide-tube inclosing said needle-valve.

20 4. In a vapor-lamp of the class described, the combination with a pair of burners, and a commingling-tube communicating with and leading upwardly from said burners, of a straight vaporizing-tube extending upwardly between said burners, an auxiliary tube carried by the upper end of said vaporizing-tube, said auxiliary tube having a curved upper end and a downwardly-extending straight portion, the upper end of said tube discharging into said commingling-chamber, and a needle-valve for opening and closing 25 the vapor-escape orifice in the end of said tube.

45 5. In a vapor-lamp of the class described, the combination with a pair of burners and a commingling-tube communicating with and

leading upwardly therefrom, of a straight vaporizing-tube leading upwardly between said burners, an auxiliary tube carried by the upper end of said vaporizing-tube, said auxiliary tube having an inwardly-curved end and a downwardly-extending straight portion, an adjustable rod extending through the straight portion of said tube, and a flexible needle-valve carried by the upper end of said rod for opening and closing the vapor-escape opening in the end of said tube.

60 6. In a vapor-lamp of the class described, the combination with a pair of burners and a commingling-tube communicating with and extending upwardly from said burners, of a straight vaporizing-tube extending upwardly between said burners, an auxiliary tube carried by the upper end of said vaporizing-tube, said auxiliary tube having a curved upper end and a downwardly-extending straight portion and discharging into the upper end of said commingling-tube, a rod extending through the straight portion of said auxiliary tube, a flexible needle-valve carried by the upper end of said rod for opening and closing the vapor-escape orifice in the end of said auxiliary tube, and an inclosing guide-tube for said needle-valve.

65 7. In a vapor-lamp of the class described, the combination with a pair of burners, and a commingling-tube communicating therewith and extending upwardly therefrom, of a straight vaporizing-tube extending upwardly between said burners, an auxiliary tube carried by the upper end of said vaporizing-tube and discharging into the upper end of said commingling-tube, a needle-valve carried in said auxiliary tube for opening and closing the vapor-escape orifice in the end thereof, and means for partitioning said auxiliary tube to form a chamber in the upper end thereof.

70 In testimony whereof I affix my signature in presence of two witnesses.

JULIUS HEILBRON.
